UNITED STATES PATENT OFFICE

MARIE AUSTER AND LOUIS AUSTER, OF NEW YORK, N. Y.

GARTER AND METHOD OF MAKING SAME

Application filed April 26, 1929. Serial No. 358,341.

The present invention relates to garters for personal wear, and in a method of producing the same; and consists in the order and arrangement of steps of procedure in making and in the combinations and arrangements of elements of the article hereinafter described and particularly set forth in the accompanying claims.

The various types of garters now in use are objectionable in that they usually cause undue tension on the muscles of the leg, absorb moisture, and this in turn creates a high degree of friction resulting in perspiration or other "body odors"; also the tension on the leg further produces heating and discomfort to the person. As a consequence of these disadvantages, the garters in turn soon rot, become stretched beyond their elastic limit, and consequently must be discarded. All of this naturally results in more or less extravagance inasmuch as one must necessarily be required to frequently purchase new garters to be free from these objections and be reasonably comfortable.

To obviate these many and serious faults, the present invention proposes to provide a garter of all one material—preferably rubber—made in a single piece, and entirely without a stitch or seam in its structure; and so designed as to provide for ventilation to those parts of the leg in immediate contact with the garter material. It is further proposed to have the garter of minimum lightness, absolutely water-proof, and more particularly adapted to be readily washable, all to the end that one may readily have at hand a clean and sanitary pair of garters as with other articles for personal wear.

Another objection in the present used garters is that they absorb moisture which soils or stains the fabric. This in turn causes them to have variable degrees of elasticity and therefore requires constant re-adjustment on the leg to avoid falling of the garter with its obvious unsightly results.

The invention further contemplates making a garter which will be in every way comfortable while worn and absolutely free from excessive binding against the leg, but on the other hand, is characterized in being cool and

light fitting. The article is one of such extreme simplicity in its construction and design that the same may be manufactured in groups or series to the end of low cost of production, so that they may be sold in 55 multiple pairs for interchangeable use and the advantages of which will be obvious.

The invention is shown by way of illustration in the accompanying drawings, 60 wherein:

Figure 1 is an elevational view of the garter.

Fig. 2 a perspective view showing the same in use.

Fig. 3 an enlarged detail view showing 65 the sock attaching portion.

Fig. 4 a transverse sectional view taken on the line 4—4 of Fig. 1.

Fig. 5 a longitudinal sectional view taken on the line 5—5 of Fig. 3.

Fig. 6 illustrates the manner of manufacturing the garters in series or group form, 70 and

Fig. 7 is a part sectional view thereof taken on the line 7—7 of Fig. 6.

Referring to the construction in further detail, the garter comprises two or more parallel strips 8 of flexible material—preferably rubber, though it will be understood that other material, such as leather, may be used 80 if desired. The strip portions 8 have connecting pieces 9 formed of the same material and all in the one piece in the process of making. It is to be here noted that the garter material is entirely without a stitch 85 or seam for the purpose heretofore explained.

At its respective ends the garter body 8 has reduced portions 10 and 13, the reduced portion 10 of which has formed integrally therewith, and in the process of making, a 90 button or otherwise headed projection 11 adapted to adjustably receive one of the apertures 12 of the strip engaging portion 13 after the manner shown in Fig. 2.

Said reduced portion 10 has an angularly 95 projecting and more thickened or enlarged part 14 which in the wearing of the garter lies substantially up-and-down or vertical, as indicated in Fig. 2, and immediately adjacent its extreme end said portion 14 has formed 100

integrally therewith a headed projection or button 15 adapted to receive the closure or engaging part 16 of the metal fastener 17 after the usual manner of devices of this character. The attachment piece 17 is constructed of spring-like and non-rustable material whose free looped ends 18 are designed to securely engage within the apertures or openings formed through the enlarged portion 19 as clearly illustrated in Figs. 3 and 5. The enlarged portion 19 is substantially pyramidal in transverse cross section whereby to obtain strength sufficient to withstand the pull of member 17, and as well to avoid 10 protruding sharp edges.

That portion of the garter strips 8 that contacts immediate with the leg of the wearer, has reduced or rounded marginal edges 20 as shown in Fig. 4. That is to say, these edges are designed with a so-called "radius" to the end that otherwise sharp edges will leave no marks on the leg, and the minimum surface only of the garter strip will contact with the body when worn, said contacting 25 surface will obviously increase or decrease accordingly as the garter is tightened or loosened on the leg.

In the process of manufacture, it is proposed to lay out or mold a plurality of the 30 garter blanks after the manner illustrated in Figs. 6 and 7. In this way, the several garter blanks in groups of any suitable number are arranged as shown and the material connecting each adjacent pair of garters is scored or 35 weakened along the line 21 to the end that the separate articles may be readily detached or separated when the entire series or sheet is taken from the mold. In the lay-out here shown it will be noted the angular portions 40 14 are equally and oppositely disposed. This is merely to provide for those worn on the right leg and left leg respectively.

In addition to producing the garters by the molding process herein described, it is also 45 proposed to produce the same by the process of die-cutting, that is to say, the garter in its substantially finished form is cut from a strip or sheet of the thin material. The garter may also be made by suitably uniting, (e. g., vulcanizing) parallel strips in their proper 50 spaced relation.

It will be understood that the invention as herein disclosed is not limited to the details of construction shown and described as these 55 may be varied without departing from the spirit of the invention as defined by the claims.

What is claimed as new is:

1. As an article of manufacture a plurality 60 of garters arranged in a sheet, said sheet being provided with weakened lines to facilitate the detachment of the garters, each garter having a reduced end portion spaced apart from the end portion of the adjacent garter 65 for adjustable attachment about the leg and

facilitating detachment of the respective garter.

2. A garter sheet comprising a plurality of individual garter elements connected at their longitudinal edges, each garter element having a terminal tab extending obliquely to the longitudinal axis of the element.

3. A garter sheet comprising a plurality of individual garter elements connected at their longitudinal edges, each garter element 75 having a terminal tab extending obliquely to the longitudinal axis of the element, some of said terminal tabs extending to the right of the longitudinal axis and others to the left of said longitudinal axis, said sheet having 80 means to facilitate separation of the garter elements from the sheet.

4. A plurality of pairs of garters connected together and formed from a single sheet of material each pair of garters having a right 85 and left connecting portion at one end of the sheet, said sheet being scored between the garters to facilitate detachment and to define the side edges thereof.

5. The method of making garters comprising 90 producing a plurality of garter elements in one operation from a single piece of elastic material and providing weakened lines in the material between the garter elements to permit them to be separately detached.

6. The method of making garters comprising forming a plurality of garter elements in one operation in a single sheet of elastic material and scoring the material between the garter elements to permit them to be 100 separately detached.

7. The method of making garters comprising forming two groups of articles all integrally connected in one and the same operation from a single piece of thin sheet rubber and providing weakened lines for facilitating the detachment of each garter.

8. A ventilated leg encircling garter comprising a pair of narrow spaced leg encircling 110 straps connected by integrally formed cross straps, the ends of said spaced parallel leg encircling straps being converged at each end of the garter into a single strap of a width less than the width of the garter one of said reduced end portions being provided with a diagonal sock engaging terminus, said garter being formed entirely of a single sheet of rubber in lay-flat condition, and integral fastening means for the respective ends of the garter.

In witness whereof, we have hereunto set our hands at Washington, District of Columbia, this twenty-fifth day of April, A. D., nineteen hundred and twenty-nine.

MARIE AUSTER.
LOUIS AUSTER.
